UNITED STATES PATENT OFFICE.

PIERRE LEON MARTIN VICTOR CALMELS, OF TOURS, FRANCE.

APPARATUS FOR THE CUT OF THE MUSTACHE.

Application filed December 1, 1926, Serial No. 152,006, and in France December 10, 1925.

It is very difficult when shaving oneself to give the mustache a regular cut and to preserve the same and in spite of much care and a great deal of time lost, the least slip 5 of the razor alters the cut. It is then necessary to shorten the mustache indefinitely in order to rectify its line or to wait for several weeks until the hairs have grown again.

The object of the present invention is to 10 provide a simple apparatus which gives the mustache the desired shape and automatically reproduces this shape without any possibility of error and without loss of time.

The invention also aims at ensuring the 15 apparatus being securely held in position during use so as to give a regular cut to the mustache.

An apparatus according to the invention is represented by way of example in the 20 accompanying drawings, in which:—

Figures 1 and 2 are front, plan and rear views respectively of this apparatus.

Figures 3, 4 and 5 show various constituent elements of this apparatus.

25 Figure 6 is a perspective view showing the apparatus in use.

The apparatus comprises an arc 1 formed by two arms 30¹, 30², articulated together by means of a screw 32 (Figure 4), engaged by a square portion 33 in square holes 34 in the arm 30¹, and having a cylindrical portion 35 also on which the arm 30² freely turns. The two arms 30¹, 30², can thus be moved apart like the legs of a compass.

35 The arms 30¹, 30² are articulated respectively at 36¹, 36² to the arms 10¹, 10² of the supporting element 10 and thus form a kind of articulated parallelogram. Notches 37 are provided on the surface of the arms 10¹, 40 10², forming projections which allow them to be held firmly in place by the teeth. Slots 38¹, 38², are provided in the vertical lugs on the arms 10¹, 10².

The guides or wings 14¹, 14², are articulated to these lugs by means of the screws 13¹, 13².

45 The apparatus described above is used as follows:—The arms 30¹, 30² are brought together or separated by turning the same 50 about the joint 35, which allows the length of the arc 1 to be adjusted as desired, and accordingly the size of the apparatus according to the width of the mouth.

Further the arrangement of screws 13¹, 55 13² and slots 38¹, 38², inserted between the guides 14¹ and 14² and the arms 10¹, 10² of

the supporting element 10, allows these guides firstly to be turned in the directions 40¹, 40² which enables the line of trim of the mustache to be altered as desired, and 60 secondly, to be moved vertically in the directions 41¹, 41², in order to adjust the height of these guides according to the thickness of the mustache.

When once the apparatus has been finally 65 adjusted according to the size of the mouth and to the trim of the mustache adopted, it is tightened up, the screws giving a good locking by reason of the square portion provided thereon.

The mustache is then lathered by means of the shaving brush along with the rest of the face, brushing the hairs on the cheek towards the mouth under the lather of soap 75 which prevents these hairs from returning to their original position.

The arc 1 is then placed in front of the lips, the V-element 10¹, 10² being held between the teeth which allows the arc 1 to be kept in position with ease under the pressure of the teeth and the lips. The two guides 14¹, 14² then press against the mustache (Figure 6) and separate the points 20 from the middle portion 21 of the same.

These pointed ends can then be easily 80 shaved off by moving the razor along the exterior faces of the guides 14¹, 14². The portion of the mustache which it is desired to retain is always protected from the razor inside the guides 14¹, 14², and that portion 90 of the mustache outside the guides can be regularly and accurately shaved off. A very regular trim or cut which is always the same is thus obtained. The automatic operation only lasts a few minutes.

The apparatus described above thus allows of shaving oneself along the desired line of trim and without any possibility of error and without loss of time.

Claims:

1. In an apparatus for determining the trim of a mustache the combination of the following parts: an arc formed by two arms adapted to be placed in front of the lips, two guide members and means of articulation inserted between said guides and the ends of the arc allowing said guide-members to be inclined relative to said arc, and, thereby, the line for trimming the points of the mustache, to be altered.

2. In an apparatus for determining the trim of a mustache the combination of the

- following parts: an arc formed by two arms adapted to be placed in front of the lips, and comprising two adjustable members allowing the length of the arc to be varied
5 according to the size of the mouth, two guide members and means of articulation inserted between said guide members and the ends of the arc.
3. In an apparatus for determining the
10 trim of a mustache the combination of the following parts: an arc formed by two arms adapted to be placed in front of the lips and comprising two arms articulated together in the manner of the legs of a compass, thus allowing the length of the arc to be altered instantaneously according to the size of the mouth, two guide members and means of articulation inserted between said guide members and the ends of said arc.
- 15 4. In an apparatus for determining the trim of a mustache the combination of the following parts: an arc formed by two arms adapted to be placed in front of the lips, two guide-members, means of articulation inserted between said guide-members and the ends of said arc and allowing said guide-members to slide perpendicularly thus, allowing the apparatus to be adjusted according to the thickness of the mustache.
- 20 5. In an apparatus for determining the trim of a mustache the combination of the following parts: an arc formed by two arms adapted to be placed in front of the lips, a supporting element adapted to engage between the lips and the teeth, means of ar-
- 30
- 35

ticulation inserted between said supporting element and said arc, two guide-members, means of articulation inserted between said guide-members and said supporting element.

6. In an apparatus for determining the trim of a mustache the combination of the following parts: an arc formed by two arms adapted to be placed in front of the lips, a supporting element adapted to be engaged between the lips and the teeth, means of articulation inserted between said supporting element and said arc, two guide-members, means of articulation inserted between said guide-members and said supporting element so as to allow the inclination of said guide-members relative, to said supporting element, and thereby, the line for trimming the pointed ends of the mustache to be altered.

7. In an apparatus for determining the trim of a mustache the combination of the following parts: an arc formed by two arms adapted to be placed in front of the lips, a V-shaped supporting element adapted to be engaged between the lips and the teeth and comprising two articulated arms, means of articulation inserted between said supporting element and said arc, two guide-members, and means of articulation inserted between said guide-members and said supporting element.

In testimony whereof I affix my signature.

PIERRE LEON MARTIN VICTOR CALMELS.
